RAILWAY CAR TRUCK CONSTRUCTION

Fred H. Spenner, St. Louis, Mo., assignor to
Scullin Steel Co., St. Louis, Mo., a corporation
of Missouri

Application December 6, 1950, Serial No. 199,441

1 Claim. (Cl. 105—197)

1

The present invention relates generally to railway car truck constructions and more particularly to a truck construction which is concerned with improving the riding and tracking characteristics thereof.

An important object of this invention is to provide a car truck in which the bolster is adapted to accommodate means for snubbing the relative motion between the truck side frame and the bolster.

It is a further important object of the present invention to provide means for obtaining a constant snubbing action during both compression and rebound action in the springs which support the bolster, whereby there is obtained improved control over the vertical, lateral and longitudinal motion of the bolster.

Still another object is to arrange spring actuated snubbing means in cooperation with a car truck bolster so that the springs are not affected by the weight of the snubbing means whereby the force of the springs is substantially constant during operating conditions of the car truck.

The invention comprehends the provision of a car truck having side frames with bolster openings between vertical columns, and a bolster member spring supported in the side frame opening, and formed with laterally opening pockets within which are operatively mounted snubbing means of spring actuated type for cooperation with the vertical columns in opposing bolster movement. The invention further comprehends the arrangement of the spring actuated snubbing means in the longitudinal plane of the bolster so that the springs in the snubber assembly may operate independently of the weight of the snubbing means or elements thereof.

The invention also includes the arrangement of bolster pockets which are adapted to open laterally in positions adjacent side frame column members on which friction wear plates are mounted so that the snubbing means mounted within the bolster pockets may effectively contact the side frame column members to produce the frictional snubbing action desired between the bolster and side frame members.

The invention further includes the herein described cooperating parts of the car truck side frame, the bolster member having the particular arrangement of bolster pockets and the disposition of the snubbing means within the bolster pockets, together with the arrangement of longitudinally crowned surfaces on either the snubbing means or defining walls of the bolster

2

pockets, as will be hereinafter more particularly described.

The advantages of the present invention may be more fully understood from the following detailed description of exemplary embodiments, reference being had to the accompanying drawing, wherein:

Fig. 1 is a longitudinal side elevational view of a railway car truck showing the side frame and bolster assembly embodying the present invention.

Fig. 2 is an enlarged, fragmentary elevational view of a car truck bolster shown in position in a side frame which, in turn, is disclosed in transverse section, this view being taken at line 2—2 of Fig. 1.

Fig. 3 is a greatly enlarged top plan view of a bolster end portion which has been partly broken away to disclose details of the bolster pocket construction and the bolster snubbing means disposed therein.

Fig. 4 is a fragmentary sectional view in elevation, showing details of the snubbing means along line 4—4 of Fig. 3.

Fig. 5 is a further fragmentary sectional elevational view of the snubbing means seen along line 5—5 of Fig. 3.

Fig. 6 is a fragmentary top plan view in section, showing in detail a modified construction of snubbing means and bolster pocket arrangement therefor; and

Fig. 7 is a further modification of snubbing means and bolster pocket which is contemplated within the scope of the invention, this view being a fragmentary top plan view similar to that of Fig. 6.

Referring now in detail to Figs. 1 and 2, the railway car truck includes a side frame 10 having the usual axle journal boxes 11 at its longitudinal ends for mounting the usual truck wheels 12. The side frame 10 comprises an upper compression member 13, a lower tension member 14 and a pair of laterally spaced, vertically directed column members 15 which, in part, define a bolster opening 16 for the side frame 10. A bolster 17 has its end portion 18 suitably mounted within the side frame opening 16 so that it may be operatively supported by the group of bolster springs 19 carried on the tension member 14.

Referring to Figs. 1, 3 and 5, it will be observed that each of the vertically directed column members 15 is formed intermediate its ends with an inwardly projecting portion 20 adapted to carry a friction wear plate 21 for a purpose herein-after to be pointed out. The end portion 18 of

the bolster 17, insertable in the side frame opening 16 below the wear plate projections 20, is formed at its opposite sides with laterally extending lugs 22 and 23 for embracing the column projecting portions 20 in the manner clearly disclosed in Fig. 3. It is to be noted that the outermost laterally projecting lugs 22 extend throughout the vertical depth of the bolster end 18, whereas the innermost lugs 23 are formed at the upper and lower portions of the bolster, as may be seen in Fig. 2.

The lugs 22 and 23 cooperate to permit a limited degree of lateral bolster movement relative to the side frame, however they are adapted to clear the columns 15 below projections 20 upon removal of springs 19 to allow assembly of the bolster.

Upon further reference to Fig. 3, the bolster end portion 18 is suitably formed to provide for the formation of a pair of pockets 24, one of which is shown in full line section. A description of one such bolster pocket will suffice, since each of the pockets is of similar form. It is to be noted, however that the pockets are reversely arranged because they are on opposite sides of the longitudinal center line or axis of the bolster. In the construction shown in Fig. 3, the bolster pocket 24 is provided with a laterally directed opening 25 located between the endmost lug 22 and the vertically spaced innermost lugs 23. The pocket is further provided with a wall portion 26 which divides it from the adjacent pocket in the opposite side of the bolster, and with other wall portions 27 and 28. The wall portion 28 acts as the pocket end closure wall, since it is positioned at the outermost end of the bolster. The wall portion 27 forms the inner wall and is located oppositely to the pocket opening 25. The wall 27 is seen to be longitudinally crowned or convexly formed to provide a slight curvature in the horizontal plane of the bolster 17. The wall is also directed at an acute angle relative to the adjacent face of the side frame column member 15, or more particularly at an acute angle to the face plane of the wear plate 21 carried by this column.

Operatively mounted within and carried upon the bottom wall or floor 29 (Fig. 4) of each of the bolster pockets 24 there is provided snubbing means (Fig. 3) in the form of a wedge shaped shoe element 30. This wedge or shoe element 30 is provided with angularly related friction faces 31 and 32 which are adapted respectively to frictionally engage the pocket wall portion 27 and the wear plate 21 carried by the side frame column member 15. In the present construction of Fig. 3, each of the shoe elements 30 is adapted to be spring pressed into surface engagement between the wear plate 21 and the inner pocket wall 27 by means of the compression spring 33. One end of the spring 33 is maintained in operative position within the bolster pocket 24 by means of the seat projection 34 carried on the end closure wall 28. The opposite end of the spring 33 is maintained in correct position with the friction shoe element 30 by means of the seat projection 35 formed in the shoe element on an inner transverse wall or rib structure 36.

By the arrangement described, the angularly disposed spring 33 serves to force the wedge or shoe element 30 against the wear plate 21 on column 15 to produce the desired frictional snubbing of the bolster movement derived from the compression and rebound flexing of the bolster springs 19. At the same time, the spring 33

serves to force the inner face 31 of the wedge or shoe element 30 against the angularly directed, longitudinally crowned pocket wall 27, thus yieldably resisting lateral movement of the bolster 17 relative to the side frame 10. The crowned form or convexity of wall 27 permits angular movement of the bolster 17 relative to the side frame 10 without cramping or compressing the wedge 30 so that it is incapable of functioning in the manner described.

Referring to the modification of Fig. 6, it can be seen that the bolster pocket 38 is provided with an outer closure wall 39 which is normal to the longitudinal axis of the bolster 17, and that wall 40 which is arranged opposite the lateral pocket opening 41 is now constructed to provide a flat or planar surface 42. The wall 40 can be seen to be directed at an acute angle relative to the plane of the wear plate 21 carried by side frame column 45. The friction wedge or shoe element 43 within pocket 38 is formed with a flat surface 44 for engagement with the wear plate 21 and with an angularly related surface 45 which, in this instance, is slightly convex or longitudinally crowned. A compression spring 46 is adapted to seat against the pocket closure wall 39 at the projection 47 and to engage with the shoe element 43 at the spring seat projection 48 formed on an intermediate wall or strut 49 thereof. The spring 46, in this modified arrangement, is positioned with its axis substantially parallel to the plane of the surface 44 of the shoe element which is in frictional engagement with the face of the wear plate 21. This location of the spring 46 develops a maximum force component in a direction normal to the surface 42 of the pocket wall 43. Therefore, the snubbing action of the wedge or shoe 43 is greatest for movement of the bolster 17 laterally of the side frame 10.

A still further modification of the present invention is disclosed in connection with Fig. 7. In this construction, the bolster end portion 18 is provided with laterally adjacent pockets 50, each pocket being formed by an outer angularly directed wall 51 and an inner closure wall 52. The pocket is provided with a lateral opening 53 adjacent the side frame column member 15 which carries the friction wear plate 21, as previously noted. The angularly directed pocket wall 51 is seen to form an acute angle with the plane of the wear plate 21, and the wall itself is provided with a flat or planar surface 54. A friction wedge or shoe element 55 is operatively mounted within the pocket 50 to have a flat face or surface thereof at 56 in frictional engagement with the wear plate 21. The opposite angularly directed surface 57 of the shoe element 55 is formed with a longitudinal crown for a purpose already described in connection with the structure shown in Fig. 3. A spring element 58 is adapted to have one end seated on the inner closure wall 52 of the pocket 50 at the seat projection 59. The opposite end of the spring 58 is positioned in the shoe element 55 at the projection 60. This arrangement produces a bolster snubbing action like that for Fig. 3, but the location and disposition of parts has been reversed.

Having now described certain preferred constructions in connection with the present invention, it will be understood that the spring pressed wedge or shoe elements cooperate with the angularly related bolster pocket wall and side frame column friction wear plate to dampen vertical oscillations of the bolster supporting springs, and that the spring pressed wedge or shoe elements

at the opposite sides of the bolster also cooperate to resist, in a yielding manner, both lateral and longitudinal movement of the bolster relative to the side frames of the car truck.

The scope of this invention is not to be limited, except as it shall be so required in accordance with the text of the appended claim:

I claim:

In a railway car truck, a side frame having a bolster opening between spaced vertically directed columns, a bolster having its end portion supported in said opening, said bolster having a pocket on each side of its longitudinal center line and adjacent the bolster end, each pocket opening adjacent a side frame column and having a pair of walls in fixed spaced relation and angularly related with the face of the adjacent column and a wall forming the pocket floor, a shoe element in each pocket having angularly

related surfaces frictionally engaging one of said angular pocket walls and the adjacent column face, and spring means bearing on the other of said angular pocket walls and said shoe to hold said shoe in engagement, said shoe being carried on said pocket floor and said spring means being free to exert a substantially constant force on said shoe.

FRED H. SPENNER.
